INVENTOR

Henry Fletcher

United States Patent Office.

HENRY FLETCHER, OF PROVIDENCE, RHODE ISLAND, ASSIGNOR TO
FLETCHER MANUFACTURING COMPANY, OF SAME PLACE.

Design No. 4,178, dated June 28, 1870.

DESIGN FOR A TRADE-MARK.

The Schedule referred to in these Letters Patent and making part of the same.

To all whom it may concern:

Be it known that I, HENRY FLETCHER, of the city and county of Providence, in the State of Rhode Island, have originated and designed a new Design for a Trade-mark Label; and I do hereby declare that the following specification, taken in connection with the drawing making a part of the same, is a full, clear, and exact description thereof.

The design for a trade-mark label herein described and shown, in the specimen annexed, is intended as a distinctive label and trade-mark for packages of shoe and boot-lacings, made by the Fletcher Manufacturing Company, of Providence, Rhode Island.

An ornamental border, *a*, defines the outer edge of the label.

The parallelogram so formed is divided by a partition line, *b*, forming a separate rectangular space at one end of the label.

In the larger space is the description of the quan-

ty and character of the laces, and in the smaller space, in large, bold figures, which can be readily distinguished when the goods are packed upon the shelves, are the figures expressive, in fractions of a yard, of the lengths of the laces.

The design resides not in the descriptive words or figures employed, but in the separation of the words describing the contents of the package from the figures expressive of the lengths of the lacings, by the division of the label by a partition line or lines, making separate spaces for each.

What I claim as my invention, and desire to secure by Letters Patent, is—

The design for a trade-mark label, substantially as herein shown and described.

HENRY FLETCHER.
